UNITED STATES PATENT OFFICE

FREDERICK F. HASKELL, OF JAMAICA PLAIN, MASSACHUSETTS, ASSIGNOR TO APEXON COMPANY, OF JAMAICA PLAIN, MASSACHUSETTS, A CORPORATION OF MASSACHUSETTS

CASEMENT WINDOW AND SCREEN THEREFOR

Application filed September 30, 1929. Serial No. 396,333.

This invention relates to casement windows and window screens therefor and it is in the nature of an improvement on the casement window and window screen which is illustrated in my co-pending application Serial No. 372,931, filed June 22, 1929.

The device illustrated in said application comprises a casement window with a window screen therefor and window-operating mechanism constructed so that the window can be opened and closed from within the room without removing the screen. This mechanism includes an operating member secured to the casement window and extending through a notch formed in the screen so that said member is accessible from the interior of the room.

In the construction shown in said patent it is necessary to make each screen with a notch to receive the operating member and this, obviously, necessitates window screens of special manufacture. By my present invention I have provided a construction wherein the same result can be secured, that is, of opening and closing the window from within the room without removing or disturbing the screen, but which does not involve any special construction of screen.

In order to give an understanding of the invention I have illustrated in the drawing thereof a selected embodiment thereof which will now be described after which the novel features will be pointed out in the appended claims.

Figs. 1 and 2 are views of a casement window showing the screen therefor and the manner of manipulating the screen for placing it in the window or removing it therefrom;

Fig. 3 is a horizontal sectional view through the casement window taken on approximately the broken line 3—3, Fig. 4;

Fig. 4 is a vertical section taken on the line 4—4, Fig. 1;

Fig. 5 is a fragmentary view, which is a front view of Fig. 4;

Fig. 6 is a fragmentary perspective view of a portion of the bottom sill of the casement frame showing the notch therein to receive the window-operating member.

Fig. 7 is a perspective view of the guide

bracket for the window-operating member.

In the drawing 1 indicates a swinging casement window and 2 indicates the metal casement frame to which the window is hinged. As herein shown the rails or sides of the casement frame are Z-bar shape in cross section and said casement frame is provided with laterally-extending arms 3 and the casement window 1 is also provided with lateral arms 4, these two arms being hinged together at 5, this being a common manner of hinging casement windows to casement frames. 6 indicates the wooden window frame in which the casement frame is set in any usual way.

The window screen is indicated generally at 7 and this is fitted to the inside of the casement frame 2 as usual in window screens.

8 indicates the lock or latch for locking the window shut and this is constructed as shown in the above-mentioned application so that it can be manipulated without disturbing the window screen. For this purpose this lock or latch 8 is pivoted to a bracket 9 that is secured to the casement frame 2 and it co-operates with a keeper 10 which is carried by the swinging casement window, the lock or latch 8 being situated on the inside of the screen and thus being operable while the screen is in place and without disturbing the screen. For further description of this construction reference may be had to the above-mentioned co-pending application Serial No. 372,931.

The swinging casement window 1 is operated through an operating member 11 which is pivoted at 12 to a lug or ear 13 secured to the casement window. This operating member 11 extends into the room and is capable of being manipulated from inside of the room. Said member is located on the bottom edge of the screen 7 when the latter is in place and extends through a notch 14 which is formed in the lower rail 15 of the casement frame. This member 11 also extends through a bracket member 16 secured inside of the lower rail 15 of the casement frame 2, said bracket member having an opening or passage 17 therethrough of a special shape which closely fits the operating member 11 in all positions thereof.

This opening 17 has a vertical dimension 100

equal to that of the member 11 and its horizontal dimension diverges from the intermediate point 18 toward each end. In other words, from the intermediate point 18 the passage 17 has the diverging walls 19, 20 leading to the inner end and the diverging walls 21, 22 leading to the outer end.

The window-operating member 11 is so designed that in all positions of the window it will just fill the passage 17 at the point 18. During the opening and closing movement of the window the outer end of the member 11 where it is pivoted to the ear 13 will move in the arc of a circle struck from the pivot 5 as a center and consequently the member 11 has a combined sliding and swinging movement. This special shape of passage 17 provides for such swinging movement of the member 11 and the latter is so shaped that in all positions thereof the edges will contact with the points 18.

Said member 11 has a varying width, it being widest at an intermediate portion and tapering slightly from the intermediate portion toward each end. The construction is such that in all different positions which the member 11 assumes the edges thereof will just engage the points 18 and thus entirely close the opening 17 so that there is no opportunity for insects to pass through this opening regardless of the position of the casement window. When the window is entirely closed the ear 13 occupies the opening 18 and fills the latter.

This bracket 16 is provided on its upper face with a notch 23 to receive the lower edge of the window screen 7 when the latter is in place. This notch is shown as extending to the operating member 11 so that when the window screen is in place it has engagement with the operating member 11 as clearly seen in Fig. 4. This construction makes it unnecessary to provide a notch in the screen itself for the passage of the member 11 and hence it obviates the requirement that the screen should be specially made as is the case with the construction shown in my above-mentioned application.

The bracket 16 is shown as being made in two parts, the lower part 24 which is provided with ears 25 that are screwed to the casement frame 2 and cap part 26 which overlies the operating member 11 and is secured to the base part 24 by suitable screws 30. The cap part 26 carries a locking screw 27 which is adapted to engage the member 11 and by which said member may be locked in any adjusted position.

When the screen 7 is in place it is retained therein on one side by the flange 9 to which the handle 8 is pivoted and on the other side by two retaining fingers 28, 29 on the opposite side of the casement frame, one at the upper end thereof and one at the lower end. The screen is put into the window by first

placing it in the inclined position shown in Fig. 1 and then entering the left hand edge thereof behind the flange 9. The screen is then swung into the vertical position as shown in Fig. 2 thus carrying the opposite edge behind the retaining finger 28. The screen may then be moved downwardly while in its vertical position thus entering it behind the other finger 29.

In the present embodiment of the invention the passage in which the member 11 operates is formed in the casement frame and said member is so situated that it is below the window screen 7 when the latter is in its operative position. Hence it is not necessary to give the window screen itself any special construction and any stock screen can be used with this casement window.

I claim:

1. A casement window comprising a casement frame, a casement window pivoted to the frame, a window screen on the inside of the casement frame, said casement frame having an opening therethrough situated below the window screen when it is in its operative position, a window-operating member connected to the casement window and extending through said opening and operable to open and close the window from the inside thereof, and a bracket member secured to the inside of the casement frame and having a passage in alignment with the opening in said frame and through which said window-operating member extends, said passage being narrowest at an intermediate portion and diverging from said portion to each end, said window-operating member having a varying width which fills the passage in all positions which the member assumes as the window is opened and closed.

2. A casement window comprising a casement frame, the sides of which have a Z-bar cross-sectional shape, a casement window pivoted to the frame, a window screen on the inside of the casement frame, said casement frame having a notch in the vertical flange of its lower rail, which notch extends below but is closed by the window screen when the latter is in operative position, a window-operating member connected to the casement window and extending through said notch and operable to open and close the window from the inside thereof, said screen resting on the window-operating member, a bracket member secured to and projecting inwardly from the inside of the casement frame and having a passage in alignment with the notch in the casement frame and through which said window-operating member extends, and means carried by the bracket to lock the window-operating member in any adjusted position.

3. A casement window structure comprising a casement frame, a casement window pivoted to the frame, a window-operating

member connected to the casement window and operable to open and close the window from the inside thereof, and a bracket member secured to the inside of the casement frame and having a passage through which said window-operating member extends, said passage being narrowest at an intermediate portion and diverging from said portion to each end, said window-operating member having a varying width which fills the passage in all positions which said member assumes as the window is opened and closed.

4. A casement window structure comprising a casement frame, a casement window pivoted to the frame, a window screen on the inside of the casement frame, a window-operating member connected to the casement window and operable to open and close the window from the inside thereof, said casement frame and screen providing between them an opening through which said window-operating member extends, and a bracket member secured to the inside of the casement frame and having a passage in alignment with said opening and through which the window-operating member also extends, said passage being narrowest at an intermediate portion and diverging from said portion to each end, said window-operating member having a varying width which fills the passage through the bracket member in all positions which the member assumes as the window is opened and closed.

In testimony whereof, I have signed my name to this specification.

FRÉDERICK F. HASKELL.
